FERTILIZER INJECTOR

John F. Keyser and James T. Wilson, both of
4402 Trail Lake Drive, Houston, Tex.
Filed May 8, 1959, Ser. No. 812,045
1 Claim. (Cl. 111—92)

This invention relates to an improved manual injector for solid particle fertilizer.

The primary object of the invention is to provide a more easily used and operated injector of this kind which is more serviceable and efficient in operation, and which includes means for positively determining amounts of fertilizer to be injected into the ground, and means for keeping clear of earth the bores made by the injector for reception of fertilizer from the injector until the injector has been withdrawn from the ground.

Another object of the invention is to provide an injector of the character indicated above which is unusually light in weight, uncomplex in construction, is composed of a small number of simple and easily assembled parts, and which can be made in rugged and durable forms at relatively low cost.

Other important objects and advantageous features of the invention will become apparent from the following description and the accompanying drawings, wherein, for purposes of illustration only, a specific form of the invention is set forth in detail.

In the drawings:

FIGURE 1 is a perspective view of a device of the invention;

FIGURE 2 is an enlarged fragmentary vertical transverse section taken through FIGURE 1, showing the injector rod in locked position;

FIGURE 3 is a further enlarged fragmentary vertical transverse section taken on the line 3—3 of FIGURE 1;

FIGURE 4 is an enlarged horizontal section taken on the line 4—4 of FIGURE 2, showing the measuring and dispensing disc in measuring position in full lines and in dispensing position in phantom lines; and

FIGURE 5 is an exploded perspective view, partly broken away and in section, showing the component parts of the device separated.

Referring in detail to the drawings, wherein like numerals designate like parts throughout the several views, the illustrated device comprises a closed hopper 10, preferably in the form of a vertically elongated, tubular open-ended casing 12, preferably of square cross section, having internal peripheral flanges 14 and 16 at its upper and lower ends, respectively. The upper end of the hopper 10 is closed by a removable cover plate 18, secured upon the upper flange 14. The cover plate 18 has therein a central circular opening 20.

Removably secured to the underside of the cover plate 18 and registered with the opening 20 is a rod lock 24 which comprises a vertical cylinder 26 having a lateral annular flange 28 on its upper end which is provided with threaded holes 30 to receive studs 32 which extend downwardly through holes 34 provided on the cover plate 18 around the opening 20. The studs 32 also extend downwardly through holes 36 in the lateral flange 38 of a rod guide 40 whereby the guide is fixed in place upon the upper side of the cover plate 18, with its round bore

2

42 registered with the opening 20 and with a round vertical axial bore 44 which extends through the rod lock cylinder 26.

The rod lock 24 is provided with a compound slot 46 which involves an upper radial portion 48 which extends outwardly from the bore 44 to the outer edge of the flange 28, a vertical portion 50 which extends from the bore 44 through a side of the cylinder 26, and a closed chordal lower portion 52, at the lower end of the vertical portion 50, and which extends in a clockwise direction around the cylinder 26 from the portion 50.

Rotating and sliding through the rod guide 40 and the rod lock 24, and centered in the opening 20 of the top plate 18, is a vertical injector rod 54 which is composed of a polygonal, preferably square upper section 56, smaller in diameter than the opening 20, and a smooth round lower section 58. The rod sections can be permanently secured together at their meeting ends, or threadedly connected together, as by a stud 60 on the upper section 56 threaded into a socket 62 in the upper end of the lower section 58. As indicated in FIGURES 2 and 3, the upper rod section 56 is long enough to put its lower end on a level below the lower end of the hopper casing 12, and the lower rod section 58 is long enough to put its lower end below the lower end of an injector tip, in the depressed position of the injector rod 54.

On and projecting laterally from the upper rod section 56 is a locking pin 64 which is located thereon, so that in the elevated position of the rod 54, the pin can be freely rotated in the opening 20 in the space 66 between the upper end of the rod lock 24 and the rod guide 40. For rotating the injector rod 54 and for elevating and depressing the same, the rod 54 has fixed on its upper end, above the guide 40, a wheel 68. For yieldably urging the rod 54 upwardly and for giving the pin 64 frictional retention in the lower chordal portion 52 of the slot 46 when positioned therein, a helical spring 70 is circumposed on the rod 54 and is compressed between the wheel 68 and the rod guide 40.

The part of the square upper section 56 of the injector rod slides non-rotatably in the squared bore 72 of a tube 74 which has fixed on its lower end a measuring and dispensing disc 76, which is smaller in diameter than the hopper casing 12. Engaged with the lower side of the lower casing flange 16 is a square hopper bottom plate 78 having a central opening 80 passing the tube 74 and having therein an arcuate concentric slot 82. The top of the disc 76 is in bearing relation to the underside of the bottom plate 78, and the disc 76 is held up in place by a square dispensing plate 84 which is provided with a central opening 86 which is larger in diameter than, and freely passes the lower injector rod section 58.

The dispensing plate 84 is held up in place and assembled to the lower end of the hopper casing 12 by a downwardly tapering funnel 88, of square cross section, having a flange 90 around its upper end which forms a receiver for the lower end of the casing, and, with the upper end of the funnel side wall 92, forms an internal shoulder 94 which supportably engages the dispensing plate 84 at its edges. Suitable means, such as screws 95 secure the flange 90 to the casing 12.

The arcuate slot 82 of the hopper bottom plate 78 is of the same size and location as an arcuate slot 96 in the disc 76, and the disc slot 96 is sometimes registrable with

the slot 82. The dispensing plate 84 is provided with a similar arcuate slot 98 which is located diametrically opposite the bottom plate slot 82. In the dispensing plate 84, at opposite sides of and spaced from the ends of its slot 82, are two arcuate rows 100 and 102, of spaced holes with which the slot 96 of the disc 76 is sometimes wholly or partially registerable.

The funnel 38 terminates at its lower end in a thickened tubular boss 104 having in its lower end a socket 106 to receive the upper end of an injector tube 106, secured in place by suitable means, such as a set screw 108. The socket 106 opens at its upper end into a reduced diameter axial bore 110 which opens through the upper end of the boss 104 and which is larger in diameter than the lower injector rod section 58. A cross bar handle 112, for use in withdrawing the device from the ground, and is steadyng the device when being thrust into the ground, is secured, at its midpoint, as indicated at 114, to a band 116 which extends around the boss 104 and is secured thereto, as by the set screw 108.

The injector tube 106 has fixed in and extending below its lower end a ground-piercing point or tip 118, which is shorter than the rod lock 24, is preferably of solid cross section, and is provided with an axial bore 120 through which the lower injector rod section 58 slides, to expose its point 122 below the lower end 124 of the tip 118. The tip is downwardly tapered to its lower end 124 and has an external groove 126 at its upper end into which the material of the injector tube 106 can be crimped, as indicated at 128, to hold the tip 118 in place. In the upper end of the tip 118 is an enlarged and downwardly tapered mouth 129 whose side wall 131 tapers from the side wall of the injector tube to the tip bore 120, so as to eliminate any possible arrestation of fertilizer at the point whereat the injector tube 106 communicates with the bore of the tip.

A cross bar 130 is adjustably secured at its midpoint on the lower part of the injector tube 106, as by means of a strap clamp 132, and is adapted to be adjusted along the tube 106, relative to the tip 118, to serve as a stop for engaging the ground, so as to limit penetration of the point 118 to the desired depth below the ground surface; and to serve as a foot rest for driving the point 118 into the ground. Dry fertilizer, in the form of granules or powdered, is introduced into the hopper 10, through an opening 134 provided in the upper part of the side wall of the hopper casing 12, which is closed by a hinged door 136.

In operation, before filling the hopper 10 with fertilizer, the injector rod 54 is positioned, by means of the wheel 68, by pushing the wheel 68 down, against the resistance of the spring 70, until the pin 64 moves down through the slot 46 in the rod lock 24 and reaches the lower chordal portion 52 and engages therein so that the slots and holes in the top plate 78, the disc 76, and the bottom plate 84 are out of registry with each other, and thereby closed to passage of fertilizer from the hopper 10 into the injector tube 106, and hence to the tip 118. After filling of the hopper 10, the wheel 68 is then turned, in a clockwise direction so as to release the pin 64 from the slot portion 52 and slide it up and out of the slot 46 and into the opening 20 in the plate 18. The wheel 68 is then turned clockwise until the dispensing and measuring disc slot 96 is registered with the top plate slot 82, so that fertilizer falls into and fills the space defined by the disc slot 96 and the bottom plate 84. It is this filling of the disc slot 96 that constitutes the charge of fertilizer to be dispensed and injected by the device in a single injection cycle or operation. To vary this charge it is necessary to change the disc 76 for a similar disc having a larger capacity slot 96, either by enlarging or reducing the size of the slot or by enlarging or reducing the thickness of the disc 76. To this end, the device 10 can be provided with a number of different discs 76. Suitable indicator means (not shown) is adapted to be applied to the handle 68 and the

hopper cover plate 18, for indicating when the dispensing and measuring slot 96 is and is not registered with the top plate slot 82.

With a charge of fertilizer confined, as above described, in the disc slot 96, the handle 68 is then rotated one-half turn clockwise, so that the slot 82 in the top plate 78 is closed by the disc 76, and the disc slot 96 registers with the bottom plate slot 98, so that the charge falls into the injector tube 106 and reaches the mouth 129 of the tip 118. Whenever it is desired to put more than one charge of fertilizer into the injector tube, the above described change-producing operations are repeated the desired number of times.

To inject the fertilizer present in the injector tube 106 and resting in the upper end of the tip 118, to the desired depth in the ground, the stop cross bar 130 is adjusted to the proper position along the tube 106 and clamped in place. The handle 68 and rod 56 are then pushed downwardly and the tip 118 is then contacted with the ground surface and foot pressure is applied upon the bar 130, so as to drive the tip 118 and the tube 106 into the ground until the bar 130 makes stop engagement with the ground surface and is held thereat. Thereupon, the handle 68 is pulled upwardly to its extreme elevated position so that the lower end 122 of the injector rod 54 is above the tip 118 and the fertilizer can fall through the tip bore 120. Thereat the rod 54 is pushed downwardly, by means of the handle 68, so that the lower rod section 58 acts as a plunger and forces the fertilizer downwardly out of the tip bore 120 into the ground hole made by the tip 118. As this is done, the handle 68 is rotated clockwise so that the pin 64 enters and is frictionally retained in the chordal portion 52 of the rod lock slot 46, whereupon upward pull on the wheel 68 pulls the device out of the ground and sets the same for another injection operation.

Although there has been shown and described herein a preferred form of the invention, it is to be understood that the invention is not necessarily confined thereto, and that any change or changes in the structure of and in the relative arrangements of components thereof are contemplated as being within the scope of the invention as defined by the appended claim.

What is claimed is:

In a manual injector for granular fertilizer, a hopper having an open upper end and an open lower end, an injector tube having an open upper end connected to the lower end of the hopper, said injector tube having a tubular ground-piercing tip on its lower end, a cover closing the upper end of the hopper, a bottom plate closing the lower end of the hopper, an injector rod, said tip having a bore smaller in diameter than the bore of the injector tube, said rod slidably and rotatably working through said cover, said bottom plate, and the bore of the tip, an operating handle on said rod above the cover plate, a second tube surrounding a limited portion of said rod above said bottom plate and extending rotatably through said bottom plate, the rod being slidably through said second tube, means connecting said second tube and said rod for rotation together, a dispensing disc fixed on the lower end of said second tube and engaged with the underside of said bottom plate, said bottom plate and said dispensing disc having dispensing slots adapted to be registered with each other, a funnel having a larger open upper end fixed to the lower end of the hopper, said funnel having a smaller lower end to which the upper end of the injector tube is fixed, a dispensing plate fixed in the upper part of the funnel and engaged with the underside of the dispensing disc, said dispensing plate having dispensing opening means out of registry with the dispensing slot of the bottom plate, said rod being rotatable to position the slot of the dispensing disc, at times in registry with the bottom plate slot and part of the opening means of the dispensing plate, retracting spring means acting between the handle and the cover plate and normally elevating

the rod out of the bore of said tip, and a rod lock mounted on the cover plate, said rod lock having a bore through which the injector rod is slidably journaled, said lock having a vertical slot opening communicating with the lock bore and having a lateral slot portion at its lower end, the rod having a pin engaged in the slot and adapted to be engaged in the lateral slot portion only in the depressed position of the injector rod, said cover plate having an opening larger in diameter than and receiving the injector rod in which said pin is rotatable in the elevated position of the injector rod.
